by a reverse movement of the finger-piece to withdraw the guide-sheet to its normally retracted position.

6. In a front-strike typewriting machine, 5 in combination, a rotative platen, a downwardly and forwardly inclined rear paper-table at the rear of the platen, a curved paper-apron beneath the platen, releasable feed-rolls co-operative with the lower side 10 of the platen, a guide-sheet insertable from the rear between the platen and the paper-apron when the feed-rolls are cast off or released and movable forward to a position in which the forward edge of the guide-sheet 15 projects to a guiding position at the front of the platen beyond the paper-apron and above the printing line for guiding a work-sheet inserted downwardly at the front of the platen between the platen and said guide- 20 sheet, a carrier to which the rear edge of the guide-sheet is attached, a cast-off device for the feed-rolls, an operating handle forming a finger-piece, operating connections between the operating handle 25 and the cast-off device for casting off the feed-rolls during the initial part of the movement of the operating handle, and operating connections between the operating handle and said carrier for withdrawing the 30 guide-sheet after the feed-rolls have been cast off.

7. In a front-strike typewriting machine, 35 in combination, a rotative platen, a paper-apron beneath the platen, releasable feed-rolls co-operative with the lower side of the platen, a guide-sheet insertable from the rear between the platen and the paper-apron when the feed-rolls are cast off or released and movable forward to a position in which the forward edge of the guide-sheet projects 40 at the front of the platen beyond the paper-apron for guiding a work-sheet inserted downwardly at the front of the platen between the platen and said guide-sheet, a carrier to which the rear edge of the guide-sheet is attached, and manually-operable 45 mechanism including a finger-piece for first casting off the feed-rolls and then by continued movement of the finger-piece 50 moving said carrier to thrust forward the guide-sheet to its guiding position between the platen and the apron, and adapted by a reverse movement of the finger-piece to withdraw the guide-sheet to its retracted position.

8. In a front-strike typewriting machine, 55 in combination, a rotative platen, a paper-apron beneath the platen, releasable feed-rolls co-operative with the lower side of the platen, a guide-sheet insertable from the rear between the platen and the paper-apron when the feed-rolls are cast off or released and movable forward to a position in which the forward edge of the guide-sheet projects 60 at the front of the platen beyond the paper-

apron and above the printing line for guiding a work-sheet inserted downwardly at the front of the platen between the platen and said guide-sheet, a carrier to which the rear edge of the guide-sheet is attached, a cast-off 70 device for the feed-rolls, an operating member connected to said carrier for inserting or withdrawing the guide-sheet, and a finger-piece connected to the cast-off device for casting off the feed-rolls during the initial 75 part of its movement and having a lost-motion connection to said operating member for subsequently withdrawing the guide-sheet after the feed-rolls have been cast off.

9. In a front-strike typewriting machine, in 80 combination, a rotative platen, a platen-frame having end walls in which the platen is journaled, a downwardly and forwardly inclined rear paper-table forming a part of the platen-frame, a curved paper-apron beneath the platen forming a forward continuation of the rear paper-table, a guide-sheet overlying the rear paper-table and insertable at its forward edge between the platen and the paper-apron and movable forward to a position in which its forward edge projects at the front of the platen beyond the paper-apron and above the printing line, a carrier-bar above the rear paper-table and to 85 which the rear edge of the guide-sheet is attached, a pair of racks guided on the platen-frame at each side of the machine and to which the ends of the carrier-bar are secured, gears engaging the racks, a transverse shaft carrying the gears and journaled on the platen-frame, an operating gear fixed upon one end of said shaft, an operating arm pivoted upon one of the end walls of the platen-frame and having gear-teeth engageable with said operating gear, and manually-operable 90 means including a finger-piece for rocking the operating arm for thereby thrusting forward the guide-sheet to its guiding position between the platen and the apron or for withdrawing the guide-sheet to 95 the retracted position.

10. In a front-strike typewriting machine, 100 in combination, a rotative platen, a platen-frame having end walls in which the platen is journaled, a downwardly and forwardly inclined rear paper-table forming a part of the platen-frame, a curved paper-apron beneath the platen forming a forward continuation of the rear paper-table, a guide-sheet overlying the rear paper-table and 105 insertable at its forward edge between the platen and the paper-apron and movable forward to a position in which its forward edge projects beyond the paper-apron and above the printing line, a carrier-bar above the rear paper-table and to which the rear edge of the guide-sheet is attached, a pair of racks guided on the platen-frame at each 110 side of the machine and to which the ends of the carrier-bar are secured, gears engaging 115 the racks guided on the platen-frame at each side of the machine and to which the ends of the carrier-bar are secured, gears engaging 120 the racks guided on the platen-frame at each side of the machine and to which the ends of the carrier-bar are secured, gears engaging 125 the racks guided on the platen-frame at each side of the machine and to which the ends of the carrier-bar are secured, gears engaging 130

UNITED STATES PATENT OFFICE.

WILLIAM F. HELMOND, OF HARTFORD, CONNECTICUT, ASSIGNOR TO UNDERWOOD
TYPEWRITER COMPANY, OF NEW YORK, N. Y., A CORPORATION OF DELAWARE.

TYPEWRITING MACHINE.

Application filed August 18, 1921. Serial No. 493,213.

a flexible temporary sheet-guide normally in a retracted position, manually-controlled means connected to said temporary sheet-guide to advance it up in front of the platen,
5 and to retract said temporary sheet-guide independently of the sheet introduced thereby, and means to hold said sheet-guide in re-

tracted position during the feeding around the platen of the sheet introduced by the aid of said temporary guide.

JOHN A. WHERRY.

Witnesses:

**ARTHUR CONDOURE,
A. C. BOSWELL.**

which fits tightly at its circumference in the recess 7, and which has a firm engagement with the screw-threads of the stem part 12 of the stud 8, as shown in Figure 4. It will be understood that the perpendicular side walls of the recess or well 7 limit the outward expansion of the yieldable or deformable ring 15, and that this greatly helps in causing this ring to be contracted inwardly to force its material between the screw-threads of the stem part 12 of the stud 8, as shown in Figure 4, to form the unifying plug or collar 14. This yieldable plug or collar 14 is of less thickness than the depth of the recess 7, so as thereby to leave a shallow countersunk space or recess 16 outward therefrom surrounding the projecting stem part 12.

The roller-device of the present invention as so far described, is now a complete article or unitary device capable of attachment to and detachment from the typewriter-carriage as a unit. In attaching this unitary roller-device of the present invention, the projecting screw-threaded stem part 12 of the stud 8 is screwed into an interiorly screw-threaded opening or hole 17 provided in the front of the front rail or bar 18 of the typewriter-carriage 19, until the outer surface of the rearward-bearing cone 4 is clamped tightly against the forward finished vertical surface 20 of the front bar 18, thereby to secure the assembled unitary roller-device firmly in place in operative position for the peripheral roller part 1 to run upon the usual transverse rod or track rail 21 which is supported in the usual way by the typewriter-frame 22.

Any time it is desired, or should become necessary, to take up end play of the bearing balls 5, which may develop or increase with the use of the machine, this may be done merely by turning up or tightening the screw-threaded attaching stud 8 on the carriage bar 18. When the attaching screw or stud 8 is tightened on the carriage-bar 18, the yieldable plug or collar 14 will yield to permit the bearing cones 3 and 4 to be drawn more closely together, for taking up the end play of the bearing balls 5, the cone-spacing member 13 at the same time yielding and becoming flattened or reduced in thickness. It is to be noted that the yielding of the yieldable cone-retaining plug or collar 14 is facilitated by the presence of the slight recess or countersink 16 which is provided in the rear or outer face of the cone 4, outward from the yieldable plug or collar 14.

Preferably, the ring or annulus 15, from which the cone-retaining plug or collar 14 is formed, should be of somewhat softer material than the cone-spacer 13, so as to avoid jamming the cones 3 and 4 too tightly against the balls 5 when pressure is brought

to bear on this ring 15 to form therefrom the unifying or cone-retaining plug 14.

Variations may be resorted to within the scope of the invention, and portions of the improvements may be used without others. 70

Having thus described my invention, I claim:

1. In a typewriter-carriage supporting and guiding roller-device having a peripheral roller part, a pair of bearing-forming cones, bearing balls retaining said roller part upon said cones, and a headed stud having a stem passing through said cones for securing the roller-device to the typewriter-carriage; the combination of a soft metal collar received completely into a recess surrounding said stem in the side of the cone non-adjacent to said head and pressed into engaging relation with said stem, said stem being provided with means enabling the engagement of said collar therewith for combining all of said parts into a unitary device for attachment to and detachment from the typewriter-carriage by means of said stud. 75 80 85 90

2. In a typewriter-carriage supporting and guiding roller-device having a peripheral roller part, a pair of bearing-forming cones, bearing balls retaining said roller part on said cones, and a headed stud having a screw-threaded stem passing through said cones; the combination of a soft metal collar received completely into a recess surrounding said stem in the side of the cone non-adjacent to said head and pressed into engaging relation with the screw-threads of said stem for combining all of said parts into a unitary device for attachment to and detachment from the typewriter-carriage by means of said screw-threaded stud. 95 100 105

3. In a typewriter-carriage supporting and guiding roller-device having a peripheral roller part, a pair of spaced bearing-forming cones, bearing balls retaining said roller part on said cones, and a headed stud having a screw-threaded stem passing through said cones; the combination of a soft metal collar received completely into a recess surrounding said stem in the side of the cone non-adjacent to said head and pressed into engaging relation with the screw-threads of said stem for combining all of said parts into a unitary device for attachment to and detachment from the typewriter-carriage by means of said screw-threaded stud, the yieldability of said collar enabling play of the balls to be taken up by tightening the screw-threaded stud on the carriage for bringing the spaced cones more closely together. 110 115 120 125

4. In a typewriter-carriage supporting and guiding roller-device having a peripheral roller part, a pair of spaced bearing-forming cones, bearing balls retaining said roller part on said cones, and headed stud 130

having a screw-threaded stem passing through said cones; the combination of a soft metal collar received completely into a recess surrounding said stem in the side of the cone non-adjacent to said head and pressed into engaging relation with the screw-threads of said stem for combining all of said parts into a unitary device for attachment to and detachment from the typewriter-carriage by means of said screw-threaded stud, said soft metal collar being of less thickness than the depth of the recess in which it is contained, the yieldability of said collar enabling play of the balls to be taken up by tightening the screw-threaded stud on the carriage for bringing the spaced cones more closely together.

5. In a typewriter-carriage supporting and guiding roller-device having a peripheral roller part, a pair of spaced bearing-forming cones, bearing balls retaining said roller part on said cones, a yieldable cone-spacer between said cones, and a headed stud having a screw-threaded stem passing through said cones and said cone-spacer; the combination of a soft metal collar received completely into a recess surrounding said stem in the side of the cone non-adjacent to said head and pressed into engaging relation with the screw-threads of said stem for combining all of said parts into a unitary device for attachment to and detachment from the typewriter-carriage by means of said screw-threaded stud, the yieldability of said collar and of said cone-spacer enabling play of the balls to be taken up by tightening the screw-threaded stud on the carriage for bringing the cones more closely together.

6. In a typewriter-carriage supporting and guiding roller-device having a peripheral roller part, a pair of bearing-forming cones, bearing balls retaining said roller part upon said cones, and a headed stud having a screw-threaded stem passing through said cones; the combination of a soft metal plug received completely into a recess surrounding said stem in the side of said cone non-adjacent to said head and pressed into engaging relation with the screw-threads of said stem and into gripping relation with the side walls of said recess, the side walls of said recess being of abrupt formation to enable said gripping relation with said soft metal plug, said plug combining all of said parts into a unitary device for attachment to and detachment from the typewriter-carriage by means of said screw-threaded stud.

7. In a typewriter-carriage supporting and guiding roller-device having a peripheral roller part, a pair of spaced bearing-forming cones, bearing balls retaining said roller part upon said cones, and a headed stud having a screw-threaded stem passing through said cones; the combination of

a soft metal plug received completely into a recess surrounding said stem in the side of said cone non-adjacent to said head and pressed into engaging relation with the screw-threads of said stem and into gripping relation with the side walls of said recess, the side walls of said recess being of abrupt formation to enable said gripping relation with said soft metal plug, said plug combining all of said parts into a unitary device for attachment to and detachment from the typewriter-carriage by means of said screw-threaded stud, said soft-metal plug being of less thickness than the depth of the recess in which it is contained, the yieldability of said plug enabling play of said balls to be taken up by tightening the screw-threaded stud on the typewriter-carriage for bringing the spaced cones more closely together.

8. In a typewriter-carriage supporting and guiding roller-device having a peripheral roller part, a pair of spaced bearing-forming cones, bearing balls retaining said roller part upon said cones, a yieldable cone-spacer between said cones, and a headed stud having a screw-threaded stem passing through said cones and said cone-spacer; the combination of a soft metal plug received completely into a recess surrounding said stem in the side of said cone non-adjacent to said head and pressed into engaging relation with the screw-threads of said stem and into gripping relation with the side walls of said recess, the side walls of said recess being of abrupt formation to enable said gripping relation with said soft metal plug, said plug combining all of said parts into a unitary device for attachment to and detachment from the typewriter-carriage by means of said screw-threaded stud, the yieldability of said plug and of said cone-spacer enabling play of said balls to be taken up by tightening the screw-threaded stud on the typewriter-carriage for bringing the cones more closely together.

9. A typewriter-carriage supporting and guiding roller-device, comprising a carriage-supporting roller, a pair of spaced bearing cones, bearing balls retaining the roller upon the cones, the cones having countersunk recesses at the outer sides thereof, a stud upon which the cones are mounted and having a cone-retaining head received into the recess in one of the cones and having a screw-threaded stem projecting beyond the outer face of the other cone, and a cone-retaining soft metal collar in the recess in the latter cone and pressed into engagement with the screw-threaded stem for combining all of said parts to form a unit which may be attached to or detached from the typewriter-carriage by means of the screw-threaded stud, the yieldability of the soft metal collar providing for taking up play of the bearing.

balls by tightening the screw-threaded stud on the typewriter-carriage.

10. A typewriter-carriage supporting and guiding roller-device, comprising a carriage-supporting roller, a pair of spaced bearing cones, bearing balls retaining the roller upon the cones, a yieldable cone-spacer interposed between the cones, the cones having similar countersunk recesses at the outer sides thereof, said recesses having abrupt side walls, a stud upon which the cones and cone-spacer are mounted and having a cone-retaining head received into the recess in one of the cones and having a screw-threaded stem 55 projecting beyond the outer face of the other cone, and a soft metal plug in the recess in the latter cone and pressed into engaging relation with the screw-threads of the stem and into gripping relation with the side walls of the recess for combining all of said parts to form a unit which may be attached to or detached from the typewriter-carriage by means of the screw-threaded stud, the yieldability of the plug and of the cone-spacer providing for taking up play of the bearing balls by tightening the screw-threaded stud on the typewriter-carriage.

11. A typewriter-carriage supporting and guiding roller-device, comprising a carriage-supporting roller provided with an interior ball-receiving groove, a pair of bearing-forming cones co-operating with said groove to form a raceway, a set of bearing balls in the raceway, a screw upon which said cones are mounted and having a retaining head at the outer side of one of said cones, the other one of said cones being provided with a countersunk recess in the outer side thereof surrounding the screw-threaded stem 30 of said screw, and a soft metal cone-retaining collar within said recess and pressed into engaging relation with the screw-threads of said screw for combining all of said assembled parts to form a unitary device 35 which may be attached to or detached from the typewriter-carriage by means of said screw.

12. A typewriter-carriage supporting and guiding roller-device comprising a carriage-supporting roller provided with an interior

ball-receiving groove, a pair of bearing-forming cones co-operating with said groove to form a raceway, a set of bearing balls in the raceway, said cones having similar countersunk recesses in the outer sides thereof, a screw upon which said cones are mounted and having a retaining head received into the recess in one of said cones and having a screw-threaded stem projecting beyond the outer face of the other of said cones, an annular cone-retaining soft metal plug within said remaining recess and pressed into engaging relation with the screw-threads of the stem of said screw, and a yieldable cone-spacer surrounding the stem of the screw between said cones, all of said assembled parts forming a unitary device held together by said screw and plug and which may be attached to or detached from the typewriter-carriage by means of said screw, said yieldable plug and yieldable spacer providing for taking up play of the bearing balls by tightening said screw on the typewriter-carriage.

13. In a typewriter-carriage supporting and guiding roller-device, the method of retaining a pair of bearing cones upon the screw-threaded stem of a headed attaching stud, consisting in countersinking a soft metal collar for said stem into the adjacent cone, and then forcing the material of said soft metal collar into interengaging locking relation with the screw-threads of said stem.

14. In a typewriter-carriage supporting and guiding roller-device, the method of retaining a pair of bearing cones upon the screw-threaded stem of a headed attaching stud, consisting in sliding an annular soft metal plug over the screw-threaded stem and inserting it into a recess in the adjacent cone, and then bringing pressure to bear upon said plug to expand the plug to fix it in the recess and at the same time to contract the opening in the plug to force the soft metal of the plug inward into interengaging locking engagement with the screw-threads of the stem.
